UNITED STATES PATENT OFFICE.

BRUNO SCHMELZER, OF JERSEY CITY, NEW JERSEY.

PROTECTOR FOR FANS AND THE LIKE.

Application filed July 23, 1924. Serial No. 727,837.

To all whom it may concern:

Be it known that I, BRUNO SCHMELZER, a citizen of the United States, and resident of Jersey City, in the county of Hudson and 5 State of New Jersey, have invented a certain new and useful Protector for Fans and the like, of which the following is a specification, the same being a full, clear, and exact description of the invention, its structure, 10 and operation.

The invention which constitutes the subject matter of this application relates to improvements in guards, fenders, or like devices for centrifugal fans, compressors, 15 air and gas pumps, fan blowers, and other kindred apparatus which are herein designated as fans, the rotatable parts of which are enclosed by a framework, and it has for its object the provision of an improved construction of fan guards whereby undue approach to the fan wheel is prevented.

Another object of the invention is to so shape the framework of the guard that the contour of the rear portion of the same 25 shall correspond to that of the edge of the fan blade.

Another object of the invention is to increase the efficiency of such fans and to eliminate the noise ordinarily incident to 30 the use of fan guards in common use.

A further object of the invention is that the air as it enters the fan shall not strike the wires forming the rear portion of the guard at a right angle.

Another object of the invention is that a substantially unobstructed passage shall be provided for the air as it is drawn into the fan.

Another object of the invention is that 40 while serving for the above named purposes it shall cost no more to make than the fan guards in ordinary use.

A still further object of the invention is the provision of a fan guard that shall be 45 of simple construction, inexpensive to manufacture, and reliable and efficient in practical use.

With the above named objects of the invention, and other objects and purposes 50 which will be described below, in view, the invention consists in the combination, arrangement, combination and operation of parts hereinafter set forth.

The noise produced by high speed centrifugal fans is in great measure caused by

the fluid being forced to pass over one or more sharp edges, especially where such sharp edges are at right angles to the flow of the air, whereupon it ceases to flow smoothly and becomes broken up into 60 whirls or eddies thus forming a turbulent mass which produces noise.

By the employment of the peculiar form of guard used by me an unobstructed channel for the even and steady movement of 65 the fluid is provided and the above named disadvantages are eliminated.

With the above considerations in mind, and with a view of overcoming the objections pointed out, I have devised the fan 70 guard shown in the drawings, illustrative of one embodiment of the invention, which accompany and form a part of this specification, and in which—

Figure 1 represents a side elevation of a 75 fan equipped with my guard; and

Figure 2 is a view of the rear face of the guard on a smaller scale.

Referring more in detail to the drawings, the numeral 1 denotes the front face of the 80 guard framework; 2 and 3 indicate the upper and lower parts of the circular body portion of the same; 4, 5 and 6 are a plurality of rear supports or braces of the guard; 7 denotes the spindle of the meter, and 8 is the hub of the fan indicated as 9; 10 represents the front of the actuating motor, and 11 indicates the channel between the supports 5 and 6 and the blades 9 of the fan. 85

The air at the suction or intake side of the fan, when drawn into my guard for the latter, flows in converging radially disposed streams or currents. In said passage the currents meet at the guard rear face with 90 but very little resistance as they pass and are divided lengthwise or longitudinally by the rear wires 5 and 6 of the guard inasmuch as the said wires are spaced ninety degrees apart and lie in and parallel with the path of the said incoming streams of air. 95

The currents now pass into the space between the rear portion of the guard and the fan, which space is designated as the channel 11, and is formed by the rear guard supports being radially inclined at the outer parts 4 thereof and the central portions of the same being deflected, recessed or dished, as at 5 and 6, to conform in general to the 100 are or contour of the edges of the fan blades 110

in order to provide a full and free passage for the entrance of the air currents which at that point begin to have a rotary motion.

As the various currents or streams of air 5 approach the revolving fan blades they become compressed and are drawn into the fan by suction with a much increased rotary motion in order to fill the partial vacuum caused by the expelling of the air forwardly 10 from the fan.

In this latter movement of the air currents through the channel 11 they meet with no 15 obstruction whatever and consequently pass through the fan with practically no noise, while at the same time the efficiency of the 20 fan itself becomes increased. It will be noted that the channel 11 is largest at the axis of the fan thereby forming an enlarged channel posterior of the fan and affording more room for the incoming streams of air to enter the fan.

In the old type or form of fan guard ordinarily used the rear supports of the guard lie in the plane of the parts 4' of the rear 25 guard supports. Under such a condition the many streams or currents of air have to enter the guard in a direction approximately corresponding to the direction of rotation of the fan wheel, and therefore strike the rear 30 supports of the guard at right angles, as the latter lie so near the fan blades, which results in noise being produced by reason of the sharp edges of the guards across which the air currents must flow.

35 By however dishing the rear supports of the guard I attain a two-fold result; namely, first, to cause the said rear supports to lie in and parallel with the incoming streams of air; and, second, to provide a full and 40 free passage for the entrance of the air currents into the fan without encountering any obstruction whatever; both of which advantages combine in eliminating noise in the practical operation of the fan.

45 I wish it to be understood that I do not desire to be limited to the particular use or the exact details of construction shown and described, for obvious modifications will occur to persons skilled in the art.

What I claim as my invention is:—

1. In a device of the class described, a casing comprising a circular wire frame or disc and a plurality of rear supports each dished rearwardly and extending from the casing rim to the spindle of the fan in a single curved line to conform to the arc or contour of the surface of a fan blade but spaced therefrom to provide, by the rearwardly extending supports lying in and parallel with the path of the entering air, a free and unobstructed channel for the air of practically equal width throughout its length before it is deflected by the rotation of the fan. 50

2. In a device of the class described, a casing supporting a circular wire frame or disc and a plurality of radially disposed rear supports each dished rearwardly and extending from the casing rim to the spindle of the fan in a single curved line to conform to the arc or contour of the surface of a fan blade but spaced therefrom to provide, by the rearwardly extending supports lying in and parallel with the path of the entering air, a free and unobstructed channel for the air of practically equal width throughout its length before it is deflected by the rotation of the fan. 60

3. In a device of the class described, a casing supporting a circular wire frame or disc and a plurality of rear supports each dished forwardly and extending from the casing rim to the spindle of the fan in a single curved line to conform to the arc or contour of the surface of a fan blade but spaced therefrom to provide, by the rearwardly extending supports lying in and parallel with the path of the entering air, a free and unobstructed channel for the air of practically equal width throughout its length before it is deflected by the rotation of the fan. 70

Signed at New York, in the county of New York and State of New York, this 22nd day of May, A. D. 1924. 75

BRUNO SCHMELZER.
